United States Patent Office.

JOHN J. KELLY, OF SLIPPERY ROCK, PENNSYLVANIA.

Letters Patent No. 88,181, dated March 23, 1869.

IMPROVED BRIDGE.

The Schedule referred to in these Letters Patent and making part of the same.

To all whom it may concern:

Be it known that I, JOHN J. KELLY, of Slippery Rock, in the county of Butler, and State of Pennsylvania, have invented a new and useful Improvement in Bridges; and I do hereby declare the following to be a full and correct description of the same, reference being had to the accompanying drawings, which make part of this specification, and in which—

Figure 1 is a side elevation of my improved bridge.

Figure 2 is a vertical section of the same.

Figure 3 is a detached view of the mode of fastening the rope in the bridge-shoe.

Like letters of reference indicate like parts in the several figures.

The nature of my invention consists—

First, in the construction of the span of the bridge of three plates, two of which are provided with flanges, in such a manner that when the three plates are bolted together, they form a hollow triangular beam, the upper side being flat and straight, and the under side an edge, to which the supports and braces are secured.

Second, in the method of attaching the supports and braces to the span, and the means of accomplishing this.

Third, in the connection of the shoes of the bridge to each other by means of a wire rope, instead of beams, as is usual, so as to make the bridge itself elastic and yielding, which rope can be tightened or slackened as occasion may require.

Fourth, in the attachment of the supports and braces at their bottom to the plates sliding on the bracing-rope.

A. A, in the drawings, represent abutments, on which the shoes B of the bridge rest.

The shoes B are connected to each other by a span, constructed of three plates, of iron or other suitable material, C D E.

The plates D and E are each provided with flanges, d d' and e e', in such a manner that when the plates are put together, d e lie flat against and are bolted to the plate C, and the flanges d' e' lie flat against and are bolted to each other, forming a hollow triangular span.

The flanges d e are riveted to the plate C, as shown at e, and the flanges d' e', to each other, by the bolts f.

To the flanges d' e' are bolted plates g, between which the upper eyed ends of supports E, and braces G H, are bolted by bolts h, in the manner shown, their lower and also eyed ends being bolted by bolts i, between the ends of plates j, which, passing around the wire rope I, form clips, which slide freely on the latter.

The wire rope I serves as a brace to the span C D E, and is provided at each end with an eye, k, held by

a staple, l, the ends of which pass through the shoes B, and are secured by nut m.

The great advantage of forming the span of three plates is, that their lower edges, d' e', form a support for the supports E and braces G H, thus forming an easy means of attaching the latter, and bringing the strain equally over the plates C D E.

As the span, by the continual strain upon it, gives, it tightens the rope I, and thus the strain is arrested, and its power brought to bear on the rope in the direction of its length, more than at right angles to the same, for the weight of anything passing over the bridge does not come upon the rope, but upon the span, the cross-braces which sustain the planking, resting on the clips j, between the supports and braces F G I, and not upon the rope I.

Any weight coming on the bridge, exerts its power first on the supports F, and then on the braces G and H, from whatever side it may come.

The braces being fastened in the clips j, which slide freely on the rope I, the power is never exerted on a few certain spots of the latter, which would soon wear those particular spots out, but over its whole surface, thus rendering the rope more durable than if the clips were fastened at certain spots on the same.

It will be easily understood that by taking out two bolts, any of the braces or supports may be removed, and new ones substituted, without disturbing any of the other parts of the bridge; and as the parts may be constructed of cast or wrought-iron, or any other suitable material, it forms at once a strong and cheap bridge.

The tension of the rope I can at any time be regulated by means of nuts m.

Having thus described my invention,

What I claim as new, and desire to secure by Letters Patent, is—

1. The span, when constructed of plates C D E, the two latter provided with flanges d d' and e e', which are arranged to form a support for the braces F G H, substantially as and for the purposes set forth.

2. The plates g, when bolted to the flanges d' e', and supporting between them the upper eyed ends of supports F and braces G H, substantially as and for the purposes set forth.

3. The clips j, when supporting the lower eyed ends of supports F and braces G H, and sliding freely on rope I, substantially as and for the purposes set forth.
